UNITED STATES PATENT OFFICE

RAY B. WHEELER AND WALTER P. CRITES, OF EL RENO, OKLAHOMA

DEVICE FOR AUTOMATICALLY CLOSING THE AIR RELEASE OR BLEEDER COCKS OF AIR BRAKES

Application filed June 17, 1929. Serial No. 371,438.

This invention relates to the air brake systems used on railroad cars and has special reference to an automatic clamp and release for the release valve operating rod of the usual brake cylinder.

In the construction of air brake apparatus it is common to employ beneath each car, a brake cylinder which is charged with air under pressure to hold the brakes in set position.

10 At times in the operation of cars and trains it is desirable to release the brakes of a particular car and to this end the brake cylinder is provided with a release valve or "bleeder" which is opened by drawing out on a valve operating rod which runs under the car to the side thereof. As ordinarily constructed, it is necessary for the brakeman or yard hand to hold this rod out until the cylinder has been bled and the brakes set.

20 One important object of the invention is to provide an automatic device, of improved construction, for holding the rod in its outwardly pulled or release position.

A second important object of the invention 25 is to provide an improved device of this class wherein, upon the completion of the "bleeding" of the cylinder, the rod will be set so that the release valve may close ready for the next time the cylinder is charged with 30 air to release the brakes.

With the above and other objects in view, as will be hereinafter apparent, the invention consists in general of certain novel details of construction and combinations of parts, hereinafter fully described, illustrated in the accompanying drawings and specifically claimed.

In the accompanying drawings, like characters of reference indicate like parts in the 40 several views, and;

Figure 1 is a side elevation of a standard form of brake cylinder equipped with the improved device.

Figure 2 is a plan view thereof.

45 Figure 3 is a section on the line 3-3 of Figure 1.

In the embodiment of the invention herein shown there is disclosed an ordinary brake cylinder 10 provided with the usual piston rod or plunger 11. This rod is connected to

the lever 12 which is known as the "floating lever" in a brake system, certain levers and links and other parts being used to connect this lever to the brake beams. Such parts are not here shown as they form no part of 55 the present invention and for the same reason the interior construction of the cylinder is not shown although those skilled in the art will understand that there is in the cylinder the usual piston which carries the plunger 60 and that the plunger is here shown in its projected or brake setting position, the cylinder behind the piston being full of air under pressure at this time. Also the cylinder is provided with the usual "bleeder" or release 65 valve 13 which is opened from either side of the car by pulling outwardly upon the valve operating rod 14 extending to that side of the car and thus actuating the respective bell crank 15 to open the valve. 70

All of the above parts are old and well known and are here shown for the purpose of illustration in the application of the parts forming the invention.

At 16 is one of the structural members of 75 a car on which rests the cylinder 10 and clamped to and extending up from this member on opposite sides of one of the valve operating rods 14 are the rod clamps 17 and 18, the former being preferably termed the fixed 80 jaw of the clamp and the latter the movable jaw thereof. A bolt 19 passes through these jaws just below the rod 14 and on one end of this bolt is a coiled compression spring 20 by means of which the upper ends of the 85 members 17 and 18 are forced together and caused to clamp the rod 14, the pressure exerted by the spring being sufficient to hold the rod in position to retain the release valve in open position after the rod has been drawn 90 outwardly by the brakeman. It will be noted that the member 18 is longer than the member 17 so that its upper end projects above the upper end of the latter.

Clamped to the outer end of the plunger 95 11 is a bracket 21 and through the upper end of this bracket extends a trip rod or push rod 22 which passes through a guide bracket suitably secured on the cylinder. It will be noted that, with the plunger protruded and 100

the brakes set, the rod terminates in spaced relation to the member 18 and is in alinement therewith.

The action of the device may now be readily understood. Suppose that it is desired to release the air from the cylinder and thus release the brakes of the car. The brakeman pulls out on the rod 14 and lets go of it. Through the action of the clamp jaws the rod

will be held in its outwardly pulled position. In this position of the rod the release valve is open and the cylinder will be bled of the compressed air therein. As the cylinder is bled the plunger will move inwardly and this action will continue until the trip rod 22 engages against the inner face of the top part of the member 18 whereupon it will push this member away from the member 17 and thus release the rod 14 so that the bleeder valve will now close and the cylinder thus be ready for charging with air. Obviously the parts are so arranged that the brakes will be released by the time the rod 14 is released from the gripping action of the clamp jaws.

There has thus been provided a simple and efficient device of the kind described and for the purpose specified.

It is obvious that minor changes may be made in the form and construction of the invention without departing from the material principles involved. It is therefore desired to include in the invention all those forms which may come within the scope claimed.

Having thus described the invention, what is claimed as new, is;

1. The combination with a brake cylinder, its plunger and its bleeder valve operating rod; of a pair of clamping jaws gripping said rod to hold the same in adjusted position, and means carried by the plunger to engage and open said jaws upon movement of the plunger to brake releasing position.

2. The combination with a brake cylinder, its plunger and its bleeder valve operating rod; of a pair of spring pressed clamping jaws one of which is movable relative to the other and which normally grip the said rod on opposite sides thereof, and means carried by said plunger to engage the movable jaw and force it away from the other jaw upon movement of the plunger to brake releasing position.

3. The combination with a brake cylinder, its plunger and its bleeder valve operating rod; of a pair of spring pressed clamping jaws one of which is movable relative to the other and which normally grip the said rod on opposite sides thereof, and a bracket clamped to the outer end of the plunger, and a trip rod carried by said bracket and extending parallel to the plunger towards and in alinement with the upper end of the movable jaw, the end of said rod being normally spaced from the said jaw and engaging the same to move the said jaw away from the

other jaw upon movement of the plunger to brake releasing position.

4. The combination with a brake cylinder, its plunger and its bleeder valve operating rod; of a pair of clamping jaws gripping said rod to hold the same in adjusted position, a beaded spring rod passing through said jaws with its head resting against one jaw and its body projecting beyond the other jaw, a spring surrounding said spring rod and bearing at one end against the last mentioned jaw, a nut threaded on said rod and bearing against the remaining end of the spring, and means carried by the plunger to engage and open said jaws upon movement of the plunger to brake setting position.
